AUTOMOBILE DOOR LOCK

Arthur S. Thompson, Ontario, Calif.

Application August 21, 1941, Serial No. 407,796

6 Claims. (Cl. 292—166)

This invention relates to a lock for an automobile door and has as one of its objects to provide a lock which may be mounted in an automobile door of conventional construction and may be secured from within the automobile or through the medium of a key by a person standing outside the automobile, the lock being also provided with a bolt adapted to be retracted by a person within the automobile or by a person standing outside the car.

Another object of the invention is to provide the lock with bolt actuating means consisting of a plunger slidable through a door and having a head at its inner end formed with a cam surface for retracting the bolt of the lock when the plunger is shifted outwardly, the plunger being urged inwardly so that the plunger may normally assume an extended position for securing the door closed.

Another object of the invention is to provide actuating means for the plunger including a lever pivotally mounted for swinging movement in the direction in which the door swings. It will thus be seen that when the handle is grasped and pull exerted thereon, it will serve to retract the plunger and then serve as a handle for pulling the door outwardly to open position and the door may be easily released and opened with one hand.

Another object of the invention is to so form the plunger and bolt that the head of the plunger has interfitting engagement with the bolt and is guided during its inward or outward movement and its cam edge at all times held in contact with a companion cam surface of the bolt.

Another object of the invention is to provide the lock with a bolt which is slidably mounted for horizontal movement from extended position to retracted position and has a renewable wear-plate for engagement by the head of the actuating plunger by means of which the bolt is shifted to its retracted position.

Another object of the invention is to provide the lock with a handle so connected with the plunger that it is drawn into a pocket formed in the outer face of the automobile door by a spring which also serves to urge the plunger inwardly, the handle being thus normally held within the pocket and prevented from rattling.

The invention is illustrated in the accompanying drawings, wherein:

Fig. 1 is a sectional view taken horizontally through the improved lock and a portion of a door, the bolt of the lock being in extended position for securing the door closed.

Fig. 2 is a view similar to Fig. 1, showing the handle swung out of its pocket and the bolt retracted to release the door.

Fig. 3 is a transverse sectional view on the line 3—3 of Fig. 1.

Fig. 4 is a sectional view on the line 4—4 of Fig. 1.

Fig. 5 is a view on the line 5—5 of Fig. 1, showing the latches in position to secure the bolt in an extended position.

Fig. 6 is a view similar to Fig. 5, showing the latches in position to release the bolt and permit retraction thereof.

Fig. 7 is a similar view showing the bolt retracted.

Fig. 8 is a view of the lock showing portions in perspective and portions in section.

Fig. 9 is a perspective view of the plunger by means of which the bolt is retracted.

Fig. 10 is a view in elevation looking at the handle and the pocket in which it fits.

Fig. 11 is a top plan view of the bolt.

Fig. 12 is a side elevation of the bolt.

Fig. 13 is a bottom plan view of the bolt.

Fig. 14 is a sectional view taken transversely through the bolt on the line 14—14 of Fig. 12.

Fig. 15 is a sectional view on the line 15—15 of Fig. 12.

Fig. 16 is a view looking down on the plunger.

Fig. 17 is a sectional view on the line 17—17 of Fig. 16.

This improved lock is primarily intended for use on the door of an automobile but it is to be understood that its use is not limited to such a door, as it may be used on the door of a refrigerator or any other door for which it is found adapted.

A portion of a door is shown in the drawings and indicated in general by the numeral 1, it being understood that the door is of conventional construction and hinged at one side, the free side of the door having an internal bar 2 formed of wood. There has also been shown a portion of a side wall of the automobile body formed with the usual doorway 3 having, at the usual location, a socket 4 to receive the bolt of the lock. The door is opened and closed in the usual manner and when closed is held shut by the bolt entering the socket.

The lock is provided with a casing 5 formed of metal and has a shell 6 detachably secured by a suitable number of screws 7 which are passed through the shell and engaged in threaded openings 8 formed in the face plate 9 forming a part 55 of the casing 5. A flange 10 extends outwardly

from the forward edge of the face plate opposite the forward end wall 11 of the shell 6, and this end wall is formed with a passage or opening 12 which registers with the socket 4 when the door is closed and through which the bolt of the lock passes for engaging in the pocket when the door is closed and the bolt is in its normally extended position. A sleeve 13 extends outwardly from the face plate 9 of the casing 5 and is of such length that when the lock is applied to the door, the sleeve passes through the bar 2 of the door and is engaged in the sleeve or neck 14 which extends partially through the bar and is carried by a socket 15 countersunk in the bar and secured to the bar by screws 16. A slot 17 is formed at the junction of one side of the sleeve 13 with the face plate and opposite the sleeve, the shell 6 is formed with a slot 18 which extends parallel to the portion of the slot 17 formed in the face and is of a length corresponding to this portion of the slot 17 and the diameter of the sleeve 13. A shield 19 is secured against the shell 6 by screws 20 and is formed with an opening 21 located rearwardly of the slot 18.

The bolt 22 extends longitudinally through the casing 5 with its bill 23 passing through the opening 12 for engagement in the socket 4 of the doorway and since the bill is formed with the usual cam surface, the bolt will be shifted inwardly to retracted position as the door is closed and then move outwardly to extended position to enter the socket and secure the door. The rear end portion of the bolt is of reduced thickness to form a shank 24 which slidably passes through an opening 25 formed in the rear wall of the shell 6 and terminates in a stem 26 to which is attached the front end of a pull rod 27. The pull rod extends transversely of the door and is to have its rear end connected with a conventional handle so that an occupant of the automobile may operate the handle and exert pull upon the rod 27 when it is desired to retract the bolt and open the door. A slot 28 having a side opening 29 is formed through the bolt and extends longitudinally thereof with its rear end terminating at the front end of the shank 24. A wear-plate 30 is mounted in the rear end portion of the slot 29 by screws 31 and has its forward end cut diagonally to form a cam surface 32 for cooperating with an actuating plunger during retraction of the bolt, as will be herein-after set forth. The rear end of the bolt and the exposed rear end of the wear plate form a shoulder 33 against which bears the upper free end of a spring 34 anchored to the lug 35 carried by the face plate 9 of the casing. This spring is in the form of a coil and its outer convolution is bent to form an arm 36 extending upwardly back of the shoulder 33 and terminating in a finger 37 bearing against the shoulder. When the bolt is drawn inwardly to retracted position, the spring is wound about the lug 35 and when the bolt is released, the spring unwinds and forces the bolt to its extended position for engagement in the socket 4 of the doorway.

In order that a person standing outside the automobile may release the lock and open the door, there has been provided a plunger 38 which is snugly received in the sleeve 13 and is slidably longitudinally therein. A flat blade or head extends from the inner end of the plunger and slidably passes through the slot 18 of the shell 6 when in the position shown in Fig. 1, the blade being engaged in the slot 17 when the plunger is drawn

outwardly to the position shown in Fig. 2. The blade is of substantially triangular formation to provide a diagonally extending edge face constituting a cam surface 40 which bears against the cam surface 32 of the wear-plate 30, as shown in Figs. 1 and 2. Referring to these figures, it will be seen that under normal conditions, the bolt is held in extended position by the spring 34 and that when the plunger is drawn outwardly, the cam surface 40 acts on the cam surface 32 and causes the bolt to be shifted inwardly to retracted position, in which position the bill 23 of the bolt is withdrawn from the socket 4 and the door may be opened.

A handle 41 is employed for drawing the plunger outwardly and for pulling the door open. This handle has its front end pivoted in the forward end of the socket 15 by a pin 42 and normally the handle extends longitudinally in the pocket with its free end portion disposed within a recess or pocket 43 formed in the shell of the door 1. A link 44 extends longitudinally in the sleeve 13 and has its inner end pivoted in the slot 45 formed in the plunger, by a pin 46. This link passes through a slot 47 formed in a disc 48 which is screwed into the outer end of the sleeve 13 and its outer end extends into a pocket 49 formed in the handle, where it is pivotally mounted by a pin 50. When the handle is grasped and pull exerted thereon to draw it out of the pocket 43, the handle swings about its pivot pin 42 and pull is exerted on the link to draw the plunger outwardly and slide the bolt to retracted position. Continued pull on the handle will then swing the door to open position. Therefore, the lock may be released and the door pulled open by the use of one hand only. When the handle is released, the spring 51, which is coiled about the link with its ends bearing against the disc 48 and the outer end of the plunger, expands and forces the plunger inwardly so that the handle will be returned to its normal position, shown in Fig. 1, and the head or blade 38 will be moved into the slot 18 and permit the spring 34 to shift the bolt longitudinally to extended position for engaging in the socket 4 when the door is closed. The springs 34 and 51 are under tension at all times and exert pressure which will yieldably hold the bolt and the plunger in the position shown in Fig. 1 of the drawings and prevent rattling noises.

It is desired to permit the bolt to be secured in its extended position, or locking position, by a person within the automobile or by a person standing outside the automobile. The latch for operation from within the automobile consists of a shaft 52 rotatably mounted through the casing above the bolt 22 and carrying an arm 53 which extends laterally from the shaft and is fixed thereto by a pin 54 passing through the sleeve 55 of the arm and through the shaft, as shown in Fig. 4, so that when the shaft is turned, the arm will be swung from the releasing position to a latching position, in which position its free end engages back of the abutment pin or lug 56 and prevents the bolt from being slid rearwardly to retracted position. A knob 57, mounted on the shaft and protruding through the opening 21 in the shield 19, serves as a turning member for the shaft and is to be grasped by the occupant of the automobile when the latch is to be moved into or out of latching position.

To permit a person standing outside the automobile to secure the bolt against movement to retracted position, there has been provided a

shaft 58 which extends transversely through the casing under the bolt and is rotatably mounted through walls of the casing. This shaft is of such length that it projects outwardly from the casing a sufficient distance to have its outer end united to or formed integral with the core 59 having its outer end exposed through the shell of the door. By inserting a key in the keyhole 61 of the lock, the shaft may be turned and an arm 62, which is fixed to the shaft by a pin 63 passing through its sleeve 64 and through the shaft, will be swung from a lowered position to a raised position and engage a latch 65 which normally rests on a pin 66. This latch is pivotally mounted by a pin 67 and extends rearwardly therefrom, its free end being formed with an upstanding bill 68 for engaging in a notch 69 formed across the under face of the bolt when the latch is swung upwardly to latching position.

In addition to serving as a support for the latch 65, the pin 66 also constitutes an abutment for engagement by the pin 63 to limit upward swinging movement of the arm 62. Downward swinging movement of the arm to lowered position is limited by engagement of the pin 63 with an abutment pin 70 projecting inwardly from the shell 6. When the arm is in its lowered position and the latch is resting on the pin 66, the bolt may be freely moved to retracted position allowing the door to be opened, but when a person inserts a key in the keyhole 61 and turns the shaft 58 to swing the arm 62 upwardly and move it into position to engage the under face of the latch 65 and swing it upwardly to dispose its bill 68 within the notch 69, the bolt will be securely held against inward movement and the door may not be opened by an unauthorized person who does not have a key to fit the lock. It will thus be seen that the bolt may be secured in its extended position by a person within the vehicle or by a person standing outside the vehicle.

Having thus described the invention, what is claimed is:

1. In combination with a door hinged at one side for swinging outwardly to open position, a lock for the door comprising a casing carried by the door and having a sleeve extending therefrom outwardly through the door, a socket exposed at the outer side of the door and having a shank extending inwardly and engaged with the sleeve, the door having a recess leading from the socket, a bolt slidable longitudinally in the casing for movement from extended locking position to retracted position, a plunger slidable in the sleeve and having its inner end engaging the bolt to retract the bolt when the plunger is drawn outwardly, a handle pivoted at one end in the socket and normally extending longitudinally in the socket and the recess of the door, the handle being connected with the outer end of the plunger for drawing the plunger outwardly when the handle is grasped and swung out of the recess and socket, and a spring for urging the plunger inwardly and yieldably holding the handle in its normal position.

2. A lock of the character described comprising a casing having an edge wall formed with an opening, a bolt slidable longitudinally in the casing for movement from extended locking position through the opening to retracted position, a spring urging the bolt forwardly to extended position, a sleeve extending from a side of the casing about an opening therein, a plunger slidable longitudinally in the sleeve, a cam extending from the inner end of the plunger transversely

through the casing and engaging the bolt for shifting the bolt to retracted position when the plunger is shifted outwardly, a mounting at the outer end of the sleeve, a handle pivoted to the mounting and extending across the outer end of the sleeve, a link extending longitudinally in the sleeve and connecting the handle with the outer end of the plunger, and a spring in the sleeve urging the plunger inwardly and yieldably holding the handle in normal position.

3. A lock of the character described comprising a casing having a forward edge wall formed with an opening, a bolt slidable longitudinally in the casing for movement from extended position through the opening to retracted position, a spring urging the bolt forwardly to extended position, a sleeve extending from a side of the casing about an opening therein, a plunger slidable longitudinally in the sleeve, a cam extending from the inner end of the plunger transversely through the casing and engaging the bolt for shifting the bolt to retracted position when the plunger is shifted outwardly, a socket extending transversely of the sleeve and having an inwardly extending hollow shank fitting about the outer end portion of said sleeve, a slotted bushing at the outer end of the shank, a handle pivoted at one end to the socket and extending transversely across the bushing, a link extending longitudinally in the sleeve with its inner end pivoted to the plunger and its outer end portion passing outwardly through the slotted bushing and pivoted to the handle to effect outward movement of the plunger and retraction of the bolt when the handle is grasped and swung outwardly, a spring in the sleeve having its outer end abutting the bushing and its inner end bearing against the plunger and urging the plunger inwardly to a position permitting movement of the bolt to its locking position, said spring yieldably holding the handle in its normal position in the socket.

4. A lock of the character described comprising a casing having a forward edge wall formed with an opening, a bolt slidable longitudinally in the casing for movement from an extended position through the opening to retracted position, a plunger slidable transversely through the casing and having a head at its inner end formed with a diagonally extending side edge face constituting a cam surface, the bolt being formed with a longitudinal slot through which the head passes, a wear plate in the slot having a diagonal cam surface, the head of the plunger having its cam surface in face to face engagement with the cam surface of the wear plate and serving to shift the bolt inwardly to retracted position when the plunger is shifted outwardly, means for shifting the plunger outwardly and effecting retraction of the bolt, a spring urging the plunger inwardly, and a spring urging the bolt to extended position as the plunger moves inwardly.

5. A lock of the character described comprising a casing having a forward edge wall formed with an opening, a bolt slidable longitudinally in the casing for movement from extended locking position through the opening to retracted position, a plunger slidable transversely through the casing and adapted to retract the bolt when shifted outwardly, a handle for shifting the plunger outwardly, and means for releasably holding the bolt in extended position consisting of a shaft rotatably mounted through the casing transversely of the bolt, a shell carried by said casing, a head for said shaft passing through an

opening in the shell and exposed for operation by a person within an automobile, an arm extending laterally from the shaft within the casing, and an abutment upon the bolt in position for engagement by the arm to secure the bolt extended when the shaft is turned in one direction.

6. A lock of the character described comprising a casing having a forward edge wall formed with an opening, a bolt slideable longitudinally in the casing for movement from extended locking position through the opening to retracted position, a plunger slideable transversely through the casing and adapted to retract the bolt when shifted outwardly, a handle for shifting the

10

plunger outwardly when moved in a direction to open a door, a spring urging the bolt toward extended position, and means for releasably holding the bolt in its extended position consisting of a shaft rotatably mounted through the casing transversely of the bolt with one end protruding from the casing and provided with turning means accessible to a person within a vehicle, a pin extending from the bolt, and an arm carried by said shaft and extending laterally therefrom in position for engaging the pin and securing the bolt in extended position when the shaft is turned in one direction.

ARTHUR S. THOMPSON.
